JAR OPENER

Joseph B. Hohmann, Forest Grove, Oreg.

Application November 26, 1937, Serial No. 176,725

1 Claim. (Cl. 81—3.1)

This invention relates to a new and useful improvement in a jar opener and has for one of its objects to provide an opener which will break the vacuum in a sealed jar before lifting the lid.

5 Another object of the invention is to provide an opener capable of opening small or wide mouth jars.

A further object of this invention is to provide an opener which will remove a jar top without 10 injury to the top, jar or the sealing gasket.

Other objects will in part be obvious and in part 15 be pointed out hereinafter.

To the attainment of the aforesaid objects and 20 ends the invention still further resides in the novel details of construction, combination and arrangement of parts, all of which will be first fully described in the following detailed description, and then be particularly pointed out in the appended claim, reference being had to the accompanying drawing in which:

25 Fig. 1 is a perspective view of a jar with my device in position to be used.

Fig. 2 is an enlarged vertical section of the top portion of a jar with my invention in its operative position.

30 Fig. 3 is a perspective view of the jar lid and gasket held by the tool, after being removed from the jar.

Fig. 4 is an inverted plan view of the tool with 35 a small mouth jar top held therein.

Fig. 5 is an enlarged detail view of the finger member inserted under a gasket.

In the drawing like numerals indicate like parts in all of the figures and the numeral 1 indicates the cover engaging member narrowed down as at 40 6 and flanged as at 7. 2 indicates a lever forked at 2a and 2b to receive the flange 7 which is pivoted to the forks at 8. The lever 2 carries a projecting finger 4 which is grooved as at 5 to allow air from outside to enter the jar. 14 indicates the entrance of the groove 5 and 15 the curved front edge of 4.

8 indicates a jar, 10 a jar cover and 11 a gasket.

A pivoted cover engaging member 12 is pro-

vided to be used on small mouth jars. It may be moved in and out of position through the slot 13.

In operation, the cover engaging member is placed in position as shown in Fig. 1 and the lever swung in toward the jar which brings the vacuum breaking finger into its position under the gasket as shown in Fig. 2, thus compressing the gasket at the place of engagement with the finger and bringing the entrance 14 of the groove 5 in position to permit air to enter the jar (see arrow Fig. 10 2). The finger 4 being curved as it is at 15 allows it to pass under the gasket without damage thereto. The vacuum being now released, the cover may be readily lifted off as shown in Fig. 3. The cover, when lifted off may be retained within 15 the grasp of the device.

The member 12 is provided so that small mouth jars may be opened. In operation the member 12 is lowered through the slot 13 so that its crotch will engage the rim of the cover at one place 20 while the flange of the member 1 engages the cover at a second place, see Fig. 4.

The device described herein is believed to embody improved safety features not found in other similar devices. There is less chance of breaking or chipping the glass jar top or cutting the gasket with this device, which breaks the vacuum before the top is lifted, than there would be with a device which prys or wedges the cover off.

25 What I claim is:

In a jar opener, a cover engaging member having a slot in its top side, an auxiliary cover engaging member pivotally mounted on said cover engaging member adapted to be moved into position through said slot, a lever pivotally mounted on said cover engaging member, a finger on said lever positioned so as to project between a jar, and the gasket and cover thereof, thus breaking the vacuum so that said cover may be removed, said cover engaging member and said auxiliary cover engaging member having separate points 30 of contact with the edge of the jar cover opposite the place where the finger engages the jar.

JOSEPH B. HOHMANN.
